UNITED STATES PATENT OFFICE.

ERIK OTTO ERIKSSON AND GUSTAV VILHELM JOHANSSON, OF STOCKHOLM, SWEDEN.

FLUID-FUEL BURNER.

Application filed May 1, 1923, Serial No. 636,004, and in Sweden February 24, 1923.

The present invention relates to a method and arrangement for heating the walls of tubular bodies for the purpose of heating fluids in contact with said walls. The characteristics of the method consist in making a mixture of gas in a state of combustion rotate in such a manner that the hot combustion gases thus generated are made to move from their place of combustion in a spiral path through the tubular body in direct contact with its walls. Every particle of the combustion gases must on account of this spiral path cover a long course, and by reason of their rotation the combustion gases are concentrated upon the walls, all of which makes for maximum utilization of the heat created by combustion for heating the walls and thus also the fluid. By regulating the rotational speed the course of the gas particles can be lengthened or shortened through the altered pitch of the spiral path. By imparting to the gases great speed in their motion relatively to the walls the coefficient of heat transfer is increased.

In the accompanying drawing are shown only by way of example some forms of construction of apparatus for carrying out the method herein described, in which drawings,

Fig. 1 is a central vertical section of an apparatus especially adapted for heating water;

Fig. 1^a is a transverse section of the doubled walled body shown in broken lines in Fig. 1;

Fig. 2 is a fragmentary vertical sectional view of a tube of a steam boiler showing the invention applied thereto;

Fig. 3 is a central vertical section showing a modified form of apparatus, especially adapted for heating a fluid other than water;

Figs. 4 and 5 are fragmentary detail views showing in sectional side elevation and plan respectively, and on an enlarged scale, the fan and its associated ring;

Fig. 6 is a vertical sectional view of a modified form of water heating apparatus;

Figs. 7 and 8 are respectively a detail sectional side view and a plan view, on an enlarged scale, of a portion of the apparatus shown in Fig. 6; and

Fig. 9 is a detail side elevation, also on an enlarged scale, of the fuel tank and control valve shown in Fig. 6.

The apparatus shown in Fig. 1 comprises

a tubular double-walled body 1, the space 2 between the walls of which the water moves from an inlet 3 towards an outlet 4. In the lower portion of the body 1 there is mounted a rotatable fan 7 to which is attached a tubular ring 5 which is slit to provide an opening 6 extending around the inner circumference. 8 is a tank containing a liquid fuel which is vaporized or carburetted in a tubular spiral 9, leading to a nozzle 10, which is so disposed as to deliver the fuel under pressure in a diagonal direction through the opening 6 into the tubular ring 5. Carburation is started e. g. by means of a blow-lamp 11. The ring 5 acts as a turbine and is propelled by the gas. The gas which rushes with very high velocity into the ring 5, rotates inside the latter until it has gathered about the same speed as the ring, after which it leaves the ring through the opening 6 in a thin layer along its entire circumference, is mixed with the air supplied by the fan 7 and ignited, thereby continuing the carburation in the tubular spiral 9. The gas mixture obtains thus at the moment of ignition a rotary movement which is transmitted to the combustion gases, which move in a spiral path through the body 1, as is indicated by the dotted line. 12 is a bonnet or cowl. In Fig. 2 is shown a tubular steam boiler b in which one tube 1^a is visible, the walls of the boiler and tube forming together a double-walled tubular body similar to that shown in Fig. 1. The arrangement of ring 5, fan 7, tubular spiral 9 and nozzle 10 is here the same as in Fig. 1, and need therefore no further description. In Fig. 1 there is shown with dashed and dotted lines an arrangement of two tubes 13, 14 within each other and a space between the two, of which the outer one 13 is closed at its lower end. The space 2 and the space between the tubes 13, 14 are at the top connected with each other by means of a tube 15. 16 is an outlet pipe at the top of the inside tube 14. When using the tubes 13, 14 the outlet 4 is naturally shut off or altogether omitted. By this arrangement additional heating surface is provided the water or fluid in this instance passing down towards the burner in the space between the tubes 13, 14 and then returning upward through the inner tube 14, the lower end of which is open. If the fluid is in the shape of steam, the latter is thus superheated. The space between the tubes 13, 14 may be subdivided by means of

vertical, radial walls 17 into a number of channels, as shown in Fig. 1^a, so that the fluid can pass down one channel and up another etc. so as to finally pass out at top 5 from the last channel or the inner tube, as the case may be.

In the apparatus shown in Fig. 3, 1^b is the tubular body which, as in Fig. 1, has double walls. In the space 2^b between the two walls 10 the fluid moves and at the lower end of this space there is a fan 18 or such like which is adapted to be propelled by a system of ring and fan identical with that of Fig. 1, so that a spiral movement is imparted to the fluid 15 in the space 2^b. Illustration of the ring and fuel coil has been omitted from Fig. 3 for the sake of clearness, the structure being identical in every respect with that shown in Fig. 1. If this fluid is in the shape of 20 air, part of this air can be passed down through a central tube 20 to the burner so as to be mixed in a pre-heated condition with the combustion gas. This extra air is taken in through radial tubes 21 at the top. On 25 the drawing is shown the fan 7 propelled by the combustion gas itself by means of the ring 5, but it can, of course, be propelled in many other ways.

In the apparatus shown in Figs. 6, 7 and 30 8 the tubular body containing the fluid to be heated consists of a spiral tube 1^c through which the water for the bath passes from the inlet 3 to the outlet 4. The water comes from the water pipe 23 fitted with a valve 22 to the inlet 3. A secondary or by-pass water pipe 24 runs to an air-bell 25 (air pressure tank), which, through the pipe 26, is in connection with the upper part of a liquid fuel tank 27, below the spiral tube 1^c. As shown 35 in Figs. 6 and 9 the fuel tank is provided with a delivery tube 31 which communicates at its upper end with a spiral tube 9^a and at its lower end with a valve housing 40 secured in the bottom of the tank and provided 40 with openings 41 in communication with said tank. The flow of fuel through the tube 31 is controlled by a needle valve 30 which projects into the end of said tube, the stem of said valve being threaded into the lower 45 end of the housing whereby the quantity of fluid passing through the tube 31 may be regulated. When turning on the water through the valve 22 a portion of it passes through the spiral tube 1^c to a shower-rose 50 28 and to a pipe 29 to, e. g., a bath tub. Another portion of the water passes upwards into the air-bell 25, which generates the necessary pressure for forcing up the liquid 55

fuel through the pipe 31 into the spiral tube 9^a. The spiral tube 9^a passes into the lower 60 part of a tank 32 which on its inside is provided with an electrical resistance 33, which by means of a cable 34 can be connected with an electric contact in the wall. From an upper portion of the tank 32 there issues the 65 nozzle 10 of the spiral tube 9. The vaporization of the liquid fuel is thus started electrically instead of with a blow lamp as in Fig. 1. The device for starting the vaporization of the liquid fuel by means of electricity can, of course, be carried out in many other ways. The spiral tube 1^c is surrounded by a tubular double wall 35 in whose hollow space the combustion air is sucked from the top downwards to the fan 7. The double 70 wall 35 forms the guide for the combustion gases which in a spiral path pass over the walls of the spiral tube 1. The action of the form of construction according to Figs. 6 to 8 is the same as according to Fig. 1, as will 75 easily be understood without any further description.

The separate parts in the arrangements shown can, of course, be varied in many ways, provided the characteristics of the invention be retained.

What we claim is:

1. A fluid-fuel burner, comprising a tubular ring mounted for rotation, said ring being split along its periphery, and a nozzle 80 extending through the split into the ring for delivering fuel thereto, the direction of the nozzle with relation to the ring being such that the fuel delivered by the nozzle will cause the ring to rotate.

2. A fluid-fuel burner, comprising a tubular ring mounted for rotation, said ring being split along its inner periphery, and a nozzle 85 extending through said split into the ring for delivering fuel thereto, the direction of the nozzle being tangential with relation to the ring whereby the fuel delivered by the nozzle will cause rotation of the ring.

3. A fluid-fuel burner, comprising a tubular ring mounted for rotation and adapted 90 to deliver fuel along its periphery, a nozzle disposed in position to deliver fuel into said ring, the direction of the nozzle with relation to the ring being such that the fuel delivered by the nozzle will cause the ring to rotate, and a spiral tube for delivering the fuel to said nozzle.

In testimony whereof we have signed our names to this specification.

ERIK OTTO ERIKSSON,

GUSTAV VILHELM JOHANSSON.
